CLAIM

The ornamental design for a waterfall console extension, as shown and described.

DESCRIPTION

FIG. 1 is a rear left perspective view of a waterfall console extension showing my new design;

FIG. 2 is a front right perspective view thereof;

FIG. 3 is a bottom right perspective view thereof;

FIG. 4 is a front elevational view thereof;

FIG. 5 is a rear elevational view thereof; and,

FIG. 6 is a left side elevational view thereof, the opposite side being a mirror image.
